(57) **CLAIM**

The ornamental design for a top of receptacle for receiving and securing packages and other items, as shown and described.

DESCRIPTION

FIG. 1 is a top, front, left side perspective view of a top of receptacle for receiving and securing packages and other items, showing our new design;

FIG. 2 is a top, rear, right side perspective view thereof, shown in an open position with a portion of the receptacle shown in broken lines being omitted for ease of illustration; and,

FIG. 3 is another top, front, left side perspective view thereof, shown in an open position.

The evenly-spaced, equal-length dashed lines represent unclaimed subject matter and form no part of the claimed design.

(Continued)

The dash-dot broken lines shown in FIGS. 1 and 2 define the bounds of the claimed design and form no part thereof.
